UNITED STATES PATENT OFFICE.

ALONZO J. AUSTIN, OF SEATTLE, WASHINGTON, ASSIGNOR OF ONE-THIRD TO DANIEL I. SALT AND ONE-THIRD TO FREEMAN F. HEATER, BOTH OF SEATTLE, WASHINGTON.

HEAD GUARD.

Application filed April 26, 1923. Serial No. 634,730.

To all whom it may concern:

Be it known that I, ALONZO J. AUSTIN, a citizen of the United States, residing at Seattle, in the county of King and State 5 of Washington, have invented certain new and useful Improvements in Head Guards, of which the following is a specification.

This invention relates to wearing apparel known as head guards which are used in 10 gymnastic boxing exercises to protect a person's head from injury.

Hitherto head guards adapted to be tied or strapped to a person's head have been constructed of a frame or body including 15 bowl shaped metal elements to cover the ears. Such ear covers are objectionable by reason of their interfering with the hearing of the wearer and in causing the ears to become hot.

20 The main object of the present invention is the improvement in the general construction of the head guard.

A further object is to provide a guard in which the wearer's ears will be freely exposed to the atmosphere but be effectively 25 protected from becoming injured by the blows of the wearer's opponent.

A further object is the improvement in the manner or means for attaching a head 30 guard to a person, with an absence of discomfort to the user.

Still other objects and advantages of the invention will appear in the following specification.

35 The invention consists in the novel construction, adaptation and combination of devices hereinafter described and claimed.

In the accompanying drawing,—

Figure 1 is a perspective view of a head 40 guard embodying my invention shown applied. Fig. 2 is a rear elevation of Fig. 1. Fig. 3 is a view partly in plan and partly in horizontal section of the same.

45 My improved head guard is constructed with side elements 5 having ear openings 6 and connected with each other at the front by a forehead element 7. Said forehead element and the forward ends of the side elements are padded as at 8.

50 Secured to or formed integral with the side elements 5 and surrounding the respective ear openings 6 are annular padded protuberances 9. Said protuberances are of sufficient thicknesses to extend outside of 55 the ears and constitute wards to prevent the

gloved hand of a boxer coming in contact with the ears. The upper portions of the rear ends of the side elements 5 are connected by an elastic band 10 and adjacent their lower edges said side elements are adapted 60 to be adjustably connected at the back by means of a strap 11 which is secured to one of the sides 5 and engaging in a buckle 12 which is secured to the other side.

13 represents a transversely arranged 65 strap secured to the side elements 5 and is adapted to extend over the wearer's head. A longitudinally disposed strap 14 is secured to the forehead element 7 at about the midwidth of the latter and thence extends rearwardly and downwardly as shown in Figs. 2 and 3.

The longitudinal strap 14 is preferably sewed as at 15 to the transverse strap 13 and thence passes through a loop attachment 16 of the elastic band 10. Adjacent to its rear end the strap 14 is provided with two spaced loops, indicated by 17 and 18, through either of which, selectively, the strap 11 may be engaged with the strap 14 according to the 70 size of the wearer's head.

19 represents a chin strap secured to the lower edge of one of the side elements 5 and engages in a buckle 20 which is secured to the lower edge of the other side element. 75 The strap 19 is preferably provided with an elastic portion 21 to enable the wearer to conveniently operate his lower jaw.

The head guard is preferably constructed of yielding material such as leather, and 80 silk floss may advantageously be used for padding so that yielding and rolling action of the same will be had under the influence of a glancing blow thereupon.

The manner of using my improved head 85 guard will, it is thought, be apparent from the foregoing description.

The guard is supported upon the wearer's head, as shown in the drawing, by means of the straps 13 and 14 and is secured to his 90 head by means of the straps 11 and 19 with the respective buckles 12 and 20.

The elevation of the guard may be regulated by threading the strap 11 through one or the other of the loops 17 and 18 and regulating the tension of the strap 11 accordingly.

100 My improved head guard affords open receptacles for the ears, does not interfere with the wearer's hearing and obviates danger of his ears being bruised or becoming what is 110

generally known as "cauliflower" ears. The padded annular protuberances surrounding the ear holes thus not only protect the ears from injury, but also serve as cushions to neutralize the shocks of blows delivered thereupon.

5 The padding of the forehead element and forward ends of the side element serve to protect the wearer from having his forehead, 10 temple or cheeks injured by arm blows or collision with his opponent. The arrangement of the strap connections, moreover, is important by enabling the head guard to be connected to the head in a convenient manner and to be worn without discomfort.

What I claim, is:—

1. A head guard comprising a body formed to expose the ears and cover the forehead and portions of the head and face adjacent to the ears of the wearer, yielding, padded protecting members carried on the outer face of the body adjacent to the ears and formed to provide encircling protuberances thereabouts, another yielding, padded protecting member carried on the outer face of the body adjacent to the aforementioned members and arranged to extend across the forehead and down the sides of the head of the wearer, and means secured to said body for supporting the guard on the head of the wearer.

2. A head guard comprising a body formed to expose the ears and cover the forehead and portions of the head and face adjacent to the ears of the wearer, padded protecting

members carried on the outer face of the body adjacent to the ears and formed to provide encircling protuberances thereabouts, a padded protecting member carried on the outer face of the body adjacent to independent of, and in front of the ear protecting members and arranged to extend across the forehead and down the sides of the head of the wearer, and means secured to said body for supporting the guard on the head of the wearer.

3. A head guard comprising a body formed with integral side and forehead elements, and provided with apertures in the side portions for exposing the ears of the wearer, padded protecting members carried on the outer face of the body and formed to provide encircling protuberances of integral continuity around said apertures, a relatively independent padded protecting member of uninterrupted continuity carried on the outer face portions of the forehead and side elements of the body and arranged with its ends extending to a point below and in front of the ears of the wearer, and means secured to said body for supporting the guard on the head of the wearer.

Signed at Seattle, Washington, this 19th day of April, 1923.

ALONZO J. AUSTIN.
